UNITED STATES PATENT OFFICE.

JOHN STEPHENSON, OF NEW YORK, N. Y.

CAR-AXLE BOX.

SPECIFICATION forming part of Letters Patent No. 296,480, dated April 8, 1884.

Application filed July 28, 1883. (No model.)

To all whom it may concern.

Be it known that I, JOHN STEPHENSON, of the city, county, and State of New York, have invented certain Improvements in Car-Axle Boxes, of which the following is a specification.

My invention relates to that class of conveyances adapted for running upon street or tram ways; and it consists in certain improvements fully described hereinafter, and illustrated in the accompanying drawings, in which—

Figure 1 is a vertical longitudinal section through the axle-box, sill, and pedestal, showing my improvements. Fig. 2 is a plan in section through the box; and Fig. 3 is a transverse section through the box, axle, and pedestal.

Until recently the running-gear for tram-cars have had the pedestals in which the axle-boxes are confined fixed and braced to the car-body; but short curves, turn-outs, and crossings, as well as irregularities in the level of the rails, have necessitated greater flexibility in the gear. To meet this necessity I construct the running-gear as follows: The car-body, of any desired form, is provided with the usual sills, I, between which and the supporting-pedestal J are confined cushions K K', which I term "super-springs," made of india-rubber or other substance capable of compression and torsion, care being taken to so construct the springs and attachments that the pedestal has contact with the body only through the elastic medium. Such connections may be variously constructed, as shown. They consist of bolts L, each passing freely through a hole, j, in the sill, through the spring K, and through cups M M', between the upper of which and the sill is interposed a cushion, N, of rubber or other material, while a similar cushion, N', is confined beneath the top plate, k, of the pedestal and the lower cup, M', which also serves as a nut to the bolt. A flanged disk or seat, O, prevents the spring K from sliding; or the latter may be held directly against the sill by friction. As the fastening-bolts L have no direct contact with the sill or pedestal and can play freely laterally, they serve simply to prevent the vertical separation of the parts. The pedestals are retained in their position with respect to the axle by the axle-box, provided with a bearing adapted

to a shoulder or collar of the axle, so as to prevent longitudinal movement of one independently of the other. Thus the axle may have 55 an annular groove, a, at the end, adapted to receive a forked check-plate, B, fitting side grooves, x, of the axle-box shell, as described in a separate application which I have made for Letters Patent. By this arrangement of 60 axles, boxes, pedestals, springs, and car-body, the pedestals have such sufficient freedom of movement in every needful direction as to permit the wheels to accommodate themselves to irregularities or deviations in the line of rails 65 without transmitting such irregular movements to the car-body. This also permits the axles to approximate the radial lines of curves, so that the wheel-flanges will occupy their proper positions in the grooves of the rails 70 without the friction and wear resulting when the axle is retained immovably at right angles to the line of the body. This permits the curve to be traveled smoothly and easily and without excessive noise. When a car enters 75 a straight portion of the track, the torsion of the springs restores the parts to their normal position.

The springs P P' at the sides of the axle-box are confined between the shelves m m and 80 the bed-plate k' of the pedestal by pintle-bolts Q, somewhat as in the construction set forth in my Letters Patent No. 238,618. In this instance, however, the pintle-bolts enter enlarged openings n in the sills, and have no direct contact with the latter, and pass through enlarged openings in cups R R'—the former interposed between the upper spring and the top plate of the pedestal, and the latter between the lower spring and a disk, r. Each 90 cup R R' is somewhat larger in diameter than is necessary to conform to the normal shape of the spring, affording room for an expansion of the latter, which will be brought into complete contact with the cup when the spring is 95 sufficiently loaded, and will then afford a practically unyielding resistance. This permits the springs to yield readily under moderate loads and secures greatly increased resistance after the spring has been re-enforced and limited in its actions by increased contact with the cup.

It will be noted that the bearing-surfaces of the springs are rounded both toward the outer

peripheries and inward toward the central openings, thereby forming central concavities, to which conform hollow bosses s' , formed upon the cups R R' and the disks r r' . By this means I prevent the springs being crushed against the pintles, avoid abrasion therewith, and relieve the pintles of a greater portion of the lateral strain. By the combination of the disk r and cup R' , the boss of one fitting into the opening of the other, I am enabled to use superposed springs of light construction in connection with restraining-cups. When desired, however, a single spring only may be used at the side of the box.

15 Tram-cars, when excessively loaded, are apt to crush the bearing-springs, so that the pedestal strikes with a disagreeable noise and destructive effect upon the top of the box. If the springs are made stronger to remedy 20 this, the running-gear will not have sufficient elasticity, and varying the forms of the side springs has not proved effective in securing the desired result.

Experiments have shown that a gum spring 25 or cushion, S , placed between the box and pedestal will obviate the above-described difficulty to a great extent. Such cushion is fitted in a socket formed in the top plate of the pedestal, preferably contracted toward the lower 30 end, or slightly dovetailed, so that the bumper-cushion may be sprung into the socket and held in suspension without any other fastening.

I therefore claim—

1. A tram-car having the body flexibly connected with its pedestals through the medium of springs capable of lateral play, arranged between the pedestals and sills, and provided with axles having annular grooves and bearings within the boxes sliding in the pedestals, 40 whereby lateral movement of the boxes with respect to the axles is prevented, substantially as set forth.

2. The combination, in a tram-car, of the sills, pedestals, intervening springs, bolts passing therethrough, and cushions at the end of each bolt, and with the two pedestals on opposite ends of the axle held in relative position by the axle-boxes locked on the journals, substantially as set forth.

3. A tram-car with pedestals receiving the 50 boxes and intervening springs, flexible elastic cushions between the car-body and the pedestals, the axle-journals locked within the boxes, and the connections arranged to permit the pedestals to change position independently as 55 the axles approximate the radial lines of curves, and to restore the pedestals to their normal positions as the car comes upon the straight portions of the track, substantially as set forth.

4. A tram-car having its axles locked in the 60 axle-boxes, and cushions secured in flanged seats, so as to permit movement of the body independent of the pedestals by which the axles and wheels are impelled, substantially as set forth.

5. A tram-car having at each side of the axle-box a spring resting on a disk, and the upper end of the spring capped by a re-enforce inverted cup, with its bottom indented into a cavity of the spring, the indentation of 70 the cup-bottom receiving the collar of the pintle, substantially as set forth.

6. A tram-car having at each side of the axle-box a spring in two or more sections, an inverted cup and disk between the springs, 75 an inverted cup above the upper spring, with central bosses upon the cup and disk interlocking each other and extending into recesses in the springs, and a central pintle extending through all the parts, substantially as set forth.

7. A car-pedestal having an elastic bumper-cushion arranged in and supported by a socket beneath the bed-plate and in suspense above the axle-box, substantially as set forth.

8. A car-pedestal having at the under side 85 of the bed-plate a socket or receptacle for retaining a bumper-cushion, substantially as specified.

In testimony whereof I have signed my name to this specification in the presence of two sub- 90 scribing witnesses.

JOHN STEPHENSON.
